INTERCOMMUNICATING TELEPHONE
SYSTEMKenneth W. Graybill, Elmhurst, Ill., assignor to
Automatic Electric Laboratories, Inc., Chicago,
Ill., a corporation of Delaware

Application March 10, 1945, Serial No. 582,045

11 Claims. (Cl. 179—31)

1 The present invention relates in general to intercommunicating telephone systems and, in particular, to systems of the common-talk selective-signaling type wherein impulse controlled means are employed for selectively connecting certain of the stations to a common talking circuit or for selectively signaling certain of the stations.

The principal object of the present invention is to provide a simple and economical system of the above character wherein separate channels are provided for transmitting speech signals in opposite directions between two connected stations whereby the transmission efficiency is raised so as to permit the use of loudspeaking equipment at one, or both, of two connected stations.

A further object of the invention is to provide an intercommunicating system including master stations and subordinate stations in which means are provided for selectively establishing communication between any master station and any subordinate station, or any other master station, under the control of an impulsive device at a calling master station; and in which circuit arrangements are provided for enabling any of the subordinate stations to selectively signal the master stations and to establish communication between a calling subordinate station and a called master station in response to an answer by the called master station. In the illustrated embodiment of the invention the subordinate stations selectively signal the master stations by code signals.

Other objects of the invention will appear upon a further perusal of the specification taken in conjunction with the accompanying drawing, which illustrates diagrammatically the apparatus and circuits involved in a system embodying the invention. Briefly described, the system comprises a plurality of master stations each provided with a conventional telephone transmitter and receiver, which may be combined in a handset, a hook or cradle switch, a buzzer, and an impulsive device, a plurality of subordinate stations each provided with a loudspeaking transmitter and receiver, and a push button, a group of counting chain relays each corresponding to one of the stations, a pair of impulsive relays for each master station, and two common relays. If desired, both the master and the subordinate stations may be equipped with loudspeaking receivers provided that close-talking transmitters are also used at the subordinate stations. Each station is connected to the relay switching equipment by three conductors. A ground connection

2 is also illustrated at each station and at the switching point. This is chiefly for convenience in drawing for it is usually preferable to employ a fourth conductor between each station and the switching point in place of the ground connections. One of these three conductors and ground, or one of these three conductors and a fourth conductor, defines a channel for transmitting speech signals from each station, and a second one of these three conductors and ground, or a second one of these three conductors and the fourth conductor, defines a channel for receiving speech signals at each station. The third conductor and ground, or the third and fourth conductors, is used for signaling. All of the relays are located at a central switching point or exchange. The first two conductors of each master station are normally connected to a pair of common leads by their corresponding counting relays. These leads are normally disconnected from each station equipment by the hookswitch thereat. The first two conductors of each subordinate station are permanently connected to the station equipment but are normally disconnected from said common leads by their corresponding counting relays.

When a master station calls a subordinate station, the transmitter and receiver at the master station are connected to said common leads by the hook switch at the master station. The impulsive device at the master station is then operated to cause the counting relays to be operated successively until the desired subordinate station is connected to said common leads, whereupon conversation may take place between the connected stations. When one master station calls a second master station the connections of the first two conductors of the second master station to the common leads are reversed when its corresponding counting relay operates so that the transmitter of each of the connected stations will be connected to the receiver of the other station when the call is answered. The counting relay operated also energizes the buzzer at the called master station over its third conductor and ground until the call is answered.

A subordinate station may call a master station by operation of the push button thereat in accordance with a predetermined code. This causes the counting relay corresponding to the calling subordinate station to be intermittently operated over the third conductor of the calling station to connect it to the common leads and to operate the buzzers at all of the master stations in accordance with the predetermined code. This

counting relay is maintained operated under the control of the called master station when the call is answered.

Referring now to the drawing, the stations designated A, B, and C are master stations and the stations designated D and E are subordinate stations. As previously mentioned, each master station comprises a conventional telephone transmitter 1 and receiver 2, a hook or cradle switch 3, a buzzer 4, and an impulsing device 5, which device may simply be a normally closed circuit push button or may be the usual telephone dial. Each subordinate station comprises a loudspeaking transmitter 6 and receiver 7, and a push button 8. The switching equipment comprises a group of counting chain relays F to K; a pair of impulsing relays for each station consisting of line relays L, N, and R, and slow release relays M, P, and S; and two common relays T and U. It is believed that the operation of the system will best be understood by a detailed description of the manner in which typical types of connections are established.

Master station to subordinate station call

Assume that a party at master station A desires to communicate with another party at subordinate station D. The handset, in which transmitter 1 and receiver 2 are mounted, at station A is lifted from the hookswitch 3 which completes a circuit from ground through transmitter 1, impulsing device 5, contacts of the hookswitch, and over conductor 21 to battery in series with relay L. The hookswitch also connects the receiver 2 to conductor 22 and disconnects buzzer 4 from conductor 23. Relay L operates over the above traced circuit and closes a circuit from ground through contacts L1, relay M, contacts M3, and contacts T4 to battery. Relay M operates, prepares a locking circuit for counting relays F to K at contacts M1, closes a holding circuit and opens its operating circuit at contacts M3, and closes a circuit to relay T at contacts M4. Relay T operates and disconnects battery from relays P and S at contacts T4. The impulsing device 5 at station A is now operated to momentarily interrupt the circuit to relay L a number of times corresponding to the call number of the desired station, which number is two in the present instance. The first restoration of relay L closes a circuit to the upper winding of relay K from ground through contacts L1, M2, F6, G6, H6, J6, and K6. Each of the counting relays is margined so as to close only its preliminary contacts, which are numbered 4, when the circuit to its upper winding is closed. Consequently relay K closes only contacts K4 which connect its lower winding to ground at contacts M1 through contacts J5, H5, G5, and F5. The lower winding of relay K is thus short-circuited until relay L reoperates at which time the two windings of relay K are energized in series causing it to operate all of its contacts. Contacts K6 transfer the impulsing lead from relay K to relay J. The closure of contacts K1 is without effect at this time since contacts T1 are open. The second restoration and reoperation of relay L causes relay J to be operated in two steps just as relay K was operated. When relay J operates completely it opens the locking circuit for relay K at contacts J5 causing relay K to restore. Since relay L remains operated following its second reoperation, relays M, T, and J will remain operated. Relay M is maintained operated during the momentary restorations of relay L due to the copper sleeve

on its core. Relay J connects the receiver 7 at station D to conductor 9 at contacts J8, and connects the transmitter 6 at station D to battery in series with relay U at contacts J2. Relay U operates and connects the transmitter 6 to conductor 10 in series with condenser 11. A two way conversation over separate oppositely directed channels may now take place between stations A and D, the party at station A speaking into transmitter 1 thereat causes corresponding speech currents to be transmitted over conductor 21, through condenser 12, and over conductor 9 to the receiver 7 at station D, which currents return over ground or an equivalent common conductor. Similarly, the party at station D speaking into transmitter 6 thereat causes corresponding speech currents to be transmitted through condenser 11 and over conductors 10 and 22 to the receiver 2 at station A, which currents return over ground or an equivalent common conductor. An impedance matching transformer is employed with each of the loudspeaking receivers 7 in order to secure the maximum output therefrom. When the conversation is completed the handset is replaced on hookswitch 3 at station A thus opening the circuit to relay L. Relay L restores, opens the circuit to relay M and closes a circuit to the upper winding of relay H through contacts M2, F6, G6, H6, and J6. Relay H operates its preliminary contacts H4. Relay M restores, opens the operating circuit to relay H at contacts M2, opens the locking circuits to relays H and J at contacts M1, and opens the circuit to relay T at contacts M4. Relays H, J, and T restore.

Master station to master station call

Assuming now that the party at master station A desires to speak to a party at master station C instead of to a party at subordinate station D, the operations are identical to those previously described except that the circuit to relay L is momentarily interrupted three times instead of twice. Consequently relay H will be operated completely after the third reoperation of relay L. When relay H operates completely it opens the locking circuit to relay J at contacts H5, reverses the connections between the common conductors 9 and 10 and the conductors 24 and 25 extending therefrom to station C at contacts H2 and H3, and closes a circuit to the buzzer 4 at station C over lead 26 at contacts H1. Buzzer 4 operates to signal the party at station C. When the call is answered by lifting the handset from the hookswitch 3 at station C a circuit is completed to relay R over conductor 24 in series with transmitter 1. Relay R operates without effect since the operating circuit for relay S is open at contacts T4 of relay T, which is maintained operated by relay M. The function of relay R is simply to furnish transmission battery to the transmitter at station C when that station is the called station. Operation of the hookswitch 3 at station C also opens the circuit to buzzer 4 thereat and connects receiver 2 to the common conductor 9 over conductor 25 and through contacts H2. A two way conversation over separate oppositely directed channels may now take place between stations A and C. The party at station A speaking into transmitter 1 thereat causes corresponding speech currents to be transmitted over conductor 21, through condenser 12, over common conductor 9, through contacts H2, and over conductor 25 to receiver 2 at station C, which currents return over ground or an equivalent com-

mon conductor. Similarly, the party at station C speaking into the transmitter 1 thereat causes corresponding speech currents to be transmitted over conductor 24, through condenser 27 and contacts H3, over common conductor 10 and conductor 22 to the receiver 2 at station A, which currents are returned over ground or an equivalent common conductor. When the conversation is completed both parties restore their handsets on the hookswitches opening the circuits to relays L and R. Relay R restores. Relay L restores, closes a circuit to the upper winding of relay G through contacts M2, F6, G6, and H6 and opens the circuit to relay M at contacts M1. Relay G operates its preliminary contacts G4. Relay G restores, opens the operating circuit to relay G at contacts M2, opens the locking circuits to relays G and H at contacts M1, and opens the circuit to relay T at contacts M4. Relays G, H, and T restore.

Subordinate station to master station call

Assuming that a party at subordinate station D desires to converse with a party at master station A, the push button 8 at station D will be momentarily operated a number of times according to a predetermined code after which it will be held operated continuously until the call is answered. When this push button is operated it closes a circuit from ground over conductor 28, through contacts T3, and through both windings of relay J to battery. Relay J operates completely each time the above circuit is closed and closes a circuit to the buzzers 4 at all of the master stations from battery through contacts J1, T1, over common lead 29, and over individual station leads such as 23 to ground through the buzzers at each station. The operation of relay J also causes relay U to operate in series with transmitter 6 but without effect at the moment. Since the code transmitted is characteristic of station A, only a party at that station will respond. When the handset at station A is lifted from the hookswitch thereat relay L is operated over a previously traced circuit. Relay L in operating brings about the operation of relays M and T as previously described. When relay M operates it closes the locking circuit to relay J from ground through contacts M1, F5, G5, H5, and J4. Prior to the closure of this locking circuit, relay J is held operated over conductor 28 by push button 8. When relay T operates it opens the operating circuit to relay J at contacts T3 and disconnects battery through contacts J1 from common lead 29 at contacts T1 to prevent further operation of the buzzers at stations B and C. The connection thus established is identical to that which resulted when station D was called by station A. When the party at station D hears the party at station A reply to the call he may release push button 8. The speech currents are transmitted over the same paths as previously traced and the release of the switching relays is effected as previously described when the handset at station A is restored on the hookswitch thereat. It should be noted that in the event that a call was being placed, or had been completed, by a master station at the time that the party at station D operated push button 8, relay T being operated would prevent the operation of relay J since the connection between this relay and conductor 28 would be open at contacts T3, thereby preventing interference with the previously initiated, or established, connection.

Although the invention has been illustrated by

a particular embodiment thereof, it should be apparent that numerous modifications may be made therein without departing from the true spirit and scope of the invention as defined in the subjoined claims.

What is claimed is:

1. In a telephone system, a plurality of telephone stations each including an impulsing device, a central station, lines extending from said central station to each of said first stations, each of said lines defining independent incoming and outgoing signal current channels, each incoming channel normally connected to the corresponding incoming channel of all other of said lines and each outgoing channel normally connected to the corresponding outgoing channel of said other lines, and switching means at said central station operative under the control of the impulsing device at any one of said first stations over the line extending thereto to associate the incoming channel of said one line with the outgoing channel of another one of said lines and to associate the outgoing channel of said one line with the incoming channel of said other one of said lines.
2. A telephone system as claimed in claim 1 in which said switching means comprises a chain of counting relays, each corresponding to one of said first stations.
3. In a telephone system, a plurality of telephone stations each including an impulsing device, a central station, lines extending therefrom to each of said first stations, a pair of relays corresponding to each of said first stations and a common selecting means in the central station, the first relay of any one of said pairs being connected in series with the impulsing device at its corresponding station over the line extending thereto in response to the initiation of a call thereat, the second relay of said one pair operative in response to the operation of said first relay to associate said common selecting means with said first relay, said common selecting means being directly operated in response to intermittent operation of said first relay associated therewith under the control of the impulsing device at the calling station to extend a connection therefrom to a called one of said stations, and circuit arrangements for individually furnishing transmission battery to the calling and called stations through the first relays of the corresponding pairs.
4. In a telephone system, a plurality of telephone stations, a central station, lines extending from said central station to each of said first stations, each of said lines including a first conductor over which signal currents are at times transmitted and a second conductor over which signal currents are at times received at the corresponding one of said first stations, switching means at said central station normally connecting the transmitting and receiving conductors of all of said lines to a pair of common conductors in like manner, said switching means being operative under the control of any of said first stations to reverse the connections between the pair of common conductors and the transmitting and receiving conductors of the line extending to any other one of said first stations whereby two way communication between any two of said first stations may be effected over separate and oppositely directed channels.
5. In an intercommunicating system, a plurality of stations each having transmitting and re-

ceiving means, each of said stations having separate transmitting and receiving circuits at times associated with the transmitting and receiving means thereat, conductors common to said stations, the transmitting and receiving circuits of all of said stations being normally connected to said common conductors in like manner, and means operative by a calling one of said stations to reverse the connections between said common conductors and the transmitting and receiving circuits of a called one of said stations whereby two way communication between any two of said stations may be effected over separate and oppositely directed channels.

6. In an intercommunicating system, a plurality of stations each having transmitting and receiving means, each of said stations having separate transmitting and receiving circuits at times associated with the transmitting and receiving means thereat, conductors common to all of said stations, the transmitting and receiving circuits of all of said stations being normally connected to said common conductors in like manner, and means operated when a call is extended between any two of said stations to reverse the connections between said common conductors and the transmitting and receiving circuits of one of said two stations whereby two way communication is effected therebetween over separate and oppositely directed channels.

7. In an intercommunicating system, a plurality of master stations each including an impulsing device and a signal device, a plurality of subordinate stations each including a switch, a central station, lines extending from each of said master stations and each of said subordinate stations to said central station, switching means at said central station operative under the control of the impulsing device at a calling one of said master stations to selectively connect said one master station in communicative relationship with any of said subordinate stations, switching means operative under the control of the switch at a calling one of said subordinate stations to operate the signal devices at all of said master stations simultaneously, the desired master station being designated by a predetermined code, the response by the desired master station connecting it in communicative relationship with said one calling subordinate station.

8. In an intercommunicating system, a plurality of master stations each including a signal device, a plurality of subordinate stations, a central station, lines extending from each of said master stations and each of said subordinate stations to said central station, switching means at said central station operative under the control of a calling one of said master stations to selectively connect it in communicative relationship with any of said subordinate stations, switching means operative under the control of a calling one of said subordinate stations to operate the signal devices at all of said master stations simultaneously, the desired master station being designated by a predetermined code, said switching means including means responsive to an answer by the desired master station for preventing further operation of said signal devices.

9. In an intercommunicating system, a plural-

ity of master stations each including a signal device, a plurality of subordinate stations, a central station, lines extending from each of said master stations and each of said subordinate stations to said central station, switching means at said central station operative under the control of a calling one of said master stations to selectively connect it in communicative relationship with any of said subordinate stations, switching means operative under the control of a calling one of said subordinate stations to operate the signal devices at all of said master stations simultaneously, and means preventing operation of said signal devices by a subordinate station when any of said master stations is in use.

10. In a telephone system, a plurality of telephone stations, a chain of counting relays each corresponding to one of said stations, means associated with each station in a first group of said stations enabling any station in the first group to sequentially operate said counting relays to selectively call another of said stations, means associated with each station in a second group of said stations at other times enabling any station in the second group to directly operate the counting relay corresponding thereto to call a station in the first group, said first means being responsive to an answer by the called station to maintain the counting relay corresponding to the calling station operated independently of said second means.

11. In an intercommunicating system, a plurality of stations each having transmitting and receiving means, each station in a first group of said stations having separate transmitting and receiving circuits at times associated with the transmitting and receiving means thereat, each station in a second group of said stations having separate transmitting and receiving circuits permanently associated with the transmitting and receiving means thereat, conductors common to all of said stations, the transmitting and receiving circuits of the first group of said stations being normally connected to said common conductors in like manner, and means operated by a calling one of said stations in the first group to reverse the connections between said common conductors and the transmitting and receiving circuits of a called station in the first group or to connect the transmitting and receiving circuits of a called station in the second group to said common conductors, whereby two way communication between said calling station and any other one of said stations may be effected over separate and oppositely directed channels.
